UNITED STATES PATENT OFFICE.

SAMUEL A. CRAIG AND BENJAMIN F. DARBYSHIRE, OF EL PASO, TEXAS.

RAILWAY-SWITCH.

1,084,730.

Specification of Letters Patent.

Patented Jan. 20. 1914.

Application filed September 27, 1913. Serial No. 792,165.

To all whom it may concern:

Be it known that we, SAMUEL A. CRAIG and BENJAMIN F. DARBYSHIRE, citizens of the United States, residing at El Paso, in the county of El Paso and State of Texas, have invented certain new and useful Improvements in Railway-Switches, of which the following is a specification, reference being had to the accompanying drawings.

10 This invention relates to new and useful improvements in railway switches and more particularly to switches which are especially adapted for use upon street railway tracks, the object of the invention being to provide 15 a switch throwing device of novel construction adapted to be operated by a tripping device carried below the car platform in position to be controlled by the motorman.

Another object of the invention is the provision of a switch operating mechanism of the above character which will possess advantages in points of efficiency and durability, is inexpensive of manufacture and at the same time is simple in construction and 25 operation.

With the above and other objects in view, this invention consists in the novel features of construction and the combination and arrangement of parts to be hereinafter more 30 fully described, pointed out in the claims and shown in the accompanying drawings, in which—

Figure 1 is a side elevation of the front end of a car illustrating the application of our invention; Fig. 2 is a top plan view of the switch; Fig. 3 is a front elevation of the operating mechanism; Fig. 4 is a detail sectional view illustrating the mounting of the switch throwing member; Fig. 5 is a top plan view; Fig. 6 is a longitudinal sectional view; and Fig. 7 is a bottom plan view.

Referring more particularly to the drawings, 1 indicates the main track rails and 2 the pivot switch point which is operated 45 by means of the reciprocating bar 3 inclosed with a suitable casing 4 arranged between the track rails. The upper face of said casing is provided with an elongated slot or opening 5 through which projects the 50 upwardly turned end of the operating bar 3. The upturned end of the operating bar 3 is provided with a head 6 and a reduced neck portion 7, the purpose of which will be more fully set forth hereinafter. From this 55 it will be seen that by the longitudinal move-

ment of the operating bar 3, the switch point 2 may be readily actuated to open or close the switch.

The upturned end of the bar 3 is adapted for engagement by means of a shoe 8 which is movably supported from beneath the platform of the car 9 and which is preferably in the form of an elongated plate tapered at one end to a point 10, which is slightly upturned with respect to the body 60 of the plate, as clearly disclosed in Fig. 6. This shoe 8 which is rigidly secured to the lower end of a vertical supporting shaft 11 is mounted for endwise and axial movement, the upper end of the same being provided with a head 12 which is arranged within the opening 13 formed in the car bottom, said opening being closed at the ends thereof, by means of the plates 14. Arranged within the opening 13 and surrounding the upper end of the shaft 11 is a coil spring 15, one end of which bears against the lowermost plate, while the upper end thereof bears against the flange of the head member 12 so as to normally retain the 70 shaft and the shoe in a raised position above the upturned end of the bar 3.

The shaft 11 is provided at its medial portion with an opening in which is arranged the transverse pin 16 having eyes 17 formed at each end thereof to which are connected the rods 18, the forward ends of said rods being connected to a second transverse pin 19 which extends through a suitable opening formed within the lower end of the 80 operating shaft 20. From this it will be seen that upon the rotation of the operating shaft 20, the shaft 11 will be rotated to move the shoe 8 from one side of the upturned end of the bar 3 to the other, so that the bar may be readily reciprocated to throw the switch point 2 toward or away from the 85 main track rail.

A retractable spring plate 21 is provided, 90 one end of which is rigidly secured to the forward end of the car platform, as shown at 22, said plate being then bent downwardly and rearwardly, as shown at 23, the rear end thereof being provided with an elongated opening 24, in which is arranged 95 the shaft 11. The rear end of the plate 21 bears upon the upper face of the transverse pin 16 so that upon the downward movement of the rear end of the plate, the shaft 11 will be forced downwardly to engage the 100 105 110

pointed end of the shoe 8, with the upturned end of the operating bar 3, to actuate the switch point.

The spring plate 21 is actuated by means 5 of a vertically disposed reciprocating rod 25, the lower end of which bears upon the medial portion of the plate and which is mounted within a suitable opening in the bottom of the car platform and provided at 10 its upper end with a head 26 to limit the downward movement of said rod when actuating the shoe. The upper end of the operating shaft is bifurcated and arranged within said bifurcation is the inner end of a 15 lever 27, which is pivotally secured to the upper end of the shaft. The outer end of said lever is adapted to be normally disposed between either set of the pins 28 according to the direction in which the switch 20 point is to be thrown.

From the above description taken in connection with the accompanying drawings, the operation of our improved switch operating device will be readily apparent as 25 follows:—Should the operator desire to leave the main track to run on to the switch, the lever 27 is removed from between one set of pins, the operating shaft 20 rotated so as to rotate the shaft 11 and dispose the 30 shoe according to the direction the car is to take, so that the shoe will engage upon the outer side of the neck portion 7, forcing the bar 3 over toward the main track rail, said bar carrying the switch point so that the 35 switch will be readily thrown to a closed position. As the car nears the switch, the operator places his foot upon the head 26 of the rod 25, downward pressure thereof forcing downwardly upon the plate 21 40 which bears against the cross pin 16 so that the shoe 8 will be moved downwardly with the plate. As the shoe engages the neck portion 7 of the upturned end of the bar 3, it will force the same in the direction opposite 45 to which the shoe is turned so that the switch point may be readily thrown to an open or closed position. As the upper end of the rod 25 is released, the coil spring 15 will readily return the shoe to its raised position, 50 the spring plate 21 also retracting and moving the rod 25 upwardly to its operative position.

From the above description taken in connection with the accompanying drawings, it 55 will be readily apparent that we have pro-

vided a simple and durable switch operating device, whereby the switch points may be quickly and readily thrown to an open or closed position without the necessity of the operator leaving the car.

It will also be apparent that the device is extremely simple in construction, and can be manufactured at a comparatively low cost.

While we have shown and described the preferred form of our invention, it will be 65 obvious that various changes in the details of construction and in the proportions may be resorted to for successfully carrying our invention into practice without sacrificing any of the novel features or departing from 70 the scope of the appended claims.

What we claim is:—

1. A device of the class described including a support having a transverse opening, a shaft having one end mounted within said 75 opening, plates closing the ends of said opening, a coil spring normally disposed between the end of the shaft and one of the plates to normally retain the end of the shaft in one end of the opening, a shoe carried by the outer end of the shaft, and means for imparting endwise and axial movement to the shaft, as and for the purpose set forth.

2. A device of the class described including a support, a shaft carried by the support 85 and capable of endwise and axial movement, a shoe carried by the outer end of the support, a transverse pin mounted in the medial portion of the shaft, an operating shaft, rods connecting the ends of said pin with 90 the operating shaft, a retractable plate having one end rigidly secured to the support and the other end bearing upon the transverse pin, means bearing against said plate to force the same into engagement with the 95 transverse pin and impart endwise movement to the shaft, means for rotating the operating shaft to impart axial movement to the shaft, as and for the purpose set forth.

In testimony whereof we hereunto affix 100 our signatures in the presence of two witnesses.
